UNITED STATES PATENT OFFICE

THOMAS C. MERRIMAN, OF TUNSTALL, ENGLAND, ASSIGNOR TO WILLIAM S. PITCAIRN
CORPORATION, A CORPORATION OF NEW YORK

DESIGN FOR A PLATE OR SIMILAR ARTICLE

Application filed October 15, 1931. Serial No. 41,396. Term of patent 3½ years.

To all whom it may concern:

Be it known that I, THOMAS C. MERRIMAN, a subject of the King of Great Britain, and resident of Tunstall, county of Stafford, England, have invented a new, original, and ornamental Design for a Plate or Similar Article, of which the following is a specification, reference being had to the accompanying drawings, forming part thereof.

In Fig. 1 of the drawings is shown, in a top plan view, a plate embodying my new design. The border ornamentation is continued throughout around the periphery. Fig. 2 is a side view of the same.

I claim:

The ornamental design for a plate or similar article, as shown and described.

THOMAS C. MERRIMAN.
